UNITED STATES PATENT OFFICE.

JOHN O'LEARY, OF BROOKLYN, NEW YORK.

DIRECTORY.

Application filed October 9, 1925. Serial No. 61,402.

This invention relates to devices for indicating streets, stations, towns and the like in their consecutive relation, acting as a directory for a traveller, strange to the locality.

One of the objects of the invention is to provide a small, compact device approximately like a common pocket watch, in which is contained an endless tape bearing 10 the names of the places along the route to be travelled, and having means to bring each name consecutively into observation.

A further object is in the provision of a pocket carried appliance in which a series 15 of frame carried, directory rolls are interchangeably engaged, permitting ready substitution, all being movable by a single means.

These and other aims and objects are attained by the novel construction and arrangement of parts hereinafter described 20 and illustrated in the accompanying drawing, forming a material part of this disclosure, and in which:—

25 Figure 1 is a partial side elevational, partial sectional view of one embodiment of the invention, the section being taken on line 1—1 of Figure 2.

Figure 2 is a sectional view taken on line 30 2—2 of Figure 1.

Figure 3 is a sectional view of a modification in construction, the section being taken on line 3—3 of Figure 4.

Figure 4 is a transverse sectional view 35 taken on line 4—4 of Figure 3.

The device as will be seen by referring to the drawing, is similar to that of a watch, in shape and proportions, and consists of a casing 10 and back 11.

40 A stem 12, provided with a conventional ring 13, is fixed at one point in the casing and directly opposite the stem is a hinge 14 by which is connected a cover 15 provided with the usual snap catch and having at its 45 center an elongated recess 16, the inreaching walls of which contain an opening 17 closed by a transparent plate 18 on the inner side.

Extending inwardly from opposite sides 50 and bottom of the casing 10 are pairs of forks 19 and engaged between each pair are lugs 20 extending from a ring frame 21 filling the space between the back 11 and cover 15.

Also formed in the ring are pairs of 55 bearings 22 and 23 containing spindles on which are mounted drums 25 and 26 carry-

ing an endless web or tape 27 provided with perforations 28 at its edges to engage pins 29 fixed in the drums, the tapes bearing a series of names of localities 30, as best seen 60 in Figure 3.

In Figures 1 and 2 the ring 21 is shown with a flattened side 31 and the spindle 24 extends through the bearing, adjacent to which is a loose disc 32 having a notch 33 65 to receive a stop 34 fixed in the frame 31, limiting the amount of movement that can be given the disc.

A tension spring 35 is arranged to draw the disc notch against the stop, at which 70 time a pin 36, set in the disc, is in position to be moved by the end of a lever 37, pivoted on a screw 38 and extending through an opening 39 in the casing 10, adjacent the ring stem 12, and provided with an operating 75 knob 40.

Held by the key 41 to the end of the spindle 24 is a ratchet wheel 42, engaged by a pawl 43 pressed into operative position by 80 a spring 44.

It will now be seen that upon swinging the lever 37, the disc will be rotated and the pawl pivoted thereon will advance the ratchet one tooth, thus conveying motion to the drums and tape carried by them. 85

In the modification shown in Figures 3 and 4, the drum 25 is provided with a ratchet 45 at one end, the teeth of which are engaged by a flat spring 46, and at the other end is a spur gear 47 in mesh with 90 a mating gear 48 pinned to a spindle 49 journaled in the ring frame 21 and having an enlarged head 50.

The head 50 is forked to receive a lug 51 formed at the end of a spindle 52, extending through the stem 12 and provided with a knurled actuating knob 53 disposed within the ring 13 and operable by the fingers of an individual to rotate the drums 100 and convey motion to the tape.

From the foregoing it will be seen that an apparatus has been disclosed whereby a movable directory may be adjusted to bring into view the names of any desired locality and if operated properly, the name of the 105 next adjacent place will appear.

Having thus described my invention, what I claim as new and desire to secure by Letters Patent, is:—

1. A device of the class described comprising a casing in the size and shape of 110 a watch, a pair of spools rotatable therein,

an endless tape trained over said spools, said tape bearing a list of localities, and clutch actuated means to manipulate said spools to exhibit the name of a locality 5 through an opening in said casing.

2. A device of the class described comprising a watch-like casing having a hinged cover containing an aperture, a frame removably engaged in said casing, a plurality 10 of rolls revolvably mounted in said frame, an endless strip of flexible material trained over the rolls, said strip bearing insignia, and a stem winder for advancing said strip progressively to disclose the lines thereon 15 consecutively through the aperture in said cover.

3. A device of the class described com-

prising a watch-like casing having a hinged cover containing an aperture, a frame removably engaged in said casing, a plurality 20 of rolls revolvably mounted in said frame, an endless strip of flexible material trained over the rolls, said strip bearing transverse lines of imprint, a stem extending through said casing to actuate said rolls whereby 25 said strip may be progressively advanced, clutch means for retaining said rolls in an adjusted position, and a transparent plate disposed in the aperture of said cover through which said lines of imprint are 30 consecutively visible.

In witness whereof I have affixed my signature.

JOHN O'LEARY.
